UNITED STATES PATENT OFFICE.

HAROLD E. NOCK, OF NEWBURYPORT, MASSACHUSETTS, ASSIGNOR TO TOWLE MANUFACTURING COMPANY, OF NEWBURYPORT, MASSACHUSETTS, A CORPORATION OF MASSACHUSETTS.

DESIGN FOR A COFFEEPOT OR ANALOGOUS ARTICLE.

Application filed October 7, 1925. Serial No. 15,054. Term of patent 7 years.

To all whom it may concern:

Be it known that I, HAROLD E. NOCK, a citizen of the United States, residing at Newburyport, in the county of Essex and Commonwealth of Massachusetts, have invented a new, original, and ornamental Design for a Coffeepot or Analogous Article, of which the following is a specification, reference being had to the accompanying drawing, forming a part thereof.

In the accompanying drawing the figure is

a view, in side elevation, of a coffee pot showing my new design.

The dominant feature of the design comprises the ornamental bands that surround the body of the coffee pot, or analogous article.

I claim:

The ornamental design for a coffeepot or analogous article, substantially as shown and described.

HAROLD E. NOCK.
